HARRY JONES, OF SUFFERN, NEW YORK, ASSIGNOR TO AMERICAN BRAKE SHOE & FOUNDRY COMPANY, OF MAHWAH, NEW JERSEY, A CORPORATION OF NEW JERSEY.

METHOD OF FORMING BRAKE-SHOES.

1,168,509.

Specification of Letters Patent. Patented Jan. 18, 1916.

Application filed June 12, 1915. Serial No. 33,646.

To all whom it may concern:

Be it known that I, HARRY JONES, a citizen of the United States, and a resident of Suffern, in the county of Rockland and 5 State of New York, have made and invented certain new and useful Improvements in Methods of Forming Brake-Shoes, of which the following is a specification.

This invention relates to a method of making 10 brake shoes, and concerns in particular the casting of segmental brake shoes of that type wherein the various sections are formed of hard and soft metals, it being among the objects of the invention to provide an economical 15 method for forming such shoes, involving but a single molding operation, and therefore requiring a minimum amount of manual labor in the production thereof.

The invention further comprehends the 20 casting of each section directly upon the previously formed, and already cooled, section, resulting in the slight isolation of each section and preventing the intermixing of the metals forming the same, so that the 25 exact, and desired, characteristics with regard to frictional qualities and wearing properties will be incorporated in each section. The casting of the sections directly upon the sub-adjacent ones, provides an efficient 30 method for forming segmental shoes in which a binding member of expanded or openwork metal extends throughout, and preferably the entire length of, the various sections.

35 Other objects and advantages will appear as the description proceeds, wherein it is to be understood that changes in the precise embodiment of the invention can be made within the scope of what is claimed without departing from the spirit thereof.

The preferred manner in which the method is carried out is disclosed in the accompanying drawings, wherein:

Figure 1 is a view in front elevation of 45 one section of the mold employed, illustrating the shoe cavities prior to the insertion of the reinforcing back and bundle of metal therein; Fig. 2 is a view in side section of two molds, arranged side by side, the one 50 being the counterpart of the other, and having contained within the shoe cavities the

reinforcing back and binding members, and adapted to receive the molten metal therein; Fig. 3 is a view in perspective of the battery of molds, securely clamped together, and 55 illustrating the manner in which a large number of shoes may be simultaneously cast.

In carrying out my novel process, a mold 5, including the cope 6 and drag 7, is provided with the shoe cavities 10, it being desirable, from an economical standpoint, to provide each mold with two shoe cavities, the molten metal for which flows down through a central duct 9. The molds are 60 so positioned that the shoe cavities 10 are arranged on end, as disclosed in Figs. 1 and 2, and a gate 8 is provided in the top wall of the mold, which communicates with the central duct 9, suitable inlet ports 11 being arranged at successive heights within the mold 70 and extend between the central duct and the shoe cavities. The number of inlet ports 11 corresponds to, and determines, the number of sections the completed shoe is to contain, 75 and are each arranged approximately centrally of the section to which they correspond.

Communicating with the brake shoe cavities 10 are the overflow ports 12 which extend through the sides of the mold and project slightly upwardly, as well as outwardly; the outermost extremities determining the height or length of each section of the completed shoe. The uppermost portion 80 of each brake shoe cavity is not provided with overflow ports, as the top of the central duct 9 acts in this capacity. The brake shoe cavities 10 are provided with the reinforcing backs 13, and with the bundles 85 of openwork or expanded metal 14, which subsequently form parts of the completed shoe, the sections being cast directly thereon.

A number of molds, as thus constituted, 95 are placed on end and rigidly bound together by the clamps 15, forming a battery of molds, so that the shoes may be cast in bulk, thereby materially reducing the cost of each shoe. The central duct 9 of each 100 mold is of considerable diameter, so that the molten metal flows to the lowermost of the

exposed inlet ports 11, and into the shoe cavities for the formation of the shoe sections. The pouring of the molten metal is continued until such time as it starts to escape from the lowermost of the overflow ports 12. This metal, which forms the lowermost section, is then allowed to cool, the metal within the overflow ports hardening, and closing them against further escapement of metal, the upward and outward slant of the overflow ports insuring the complete closing and stoppage thereof, preventing the escapement of the metals which form the superimposed section. The metal which is to form the next section is then introduced within the shoe cavities in such quantities as to fill the same up to the next adjacent overflow port, and in such manner, the body of the shoe is built up.

20 The temperature to which the sections are allowed to cool and set prior to the casting of the next adjacent superimposed sections may be varied, as desired, it being only necessary that the previously cast sections be 25 sufficiently hard to prevent the intermingling of the metals as the next section is poured.

The metal which forms each section is allowed to cool prior to the casting of the next adjacent and superimposed section, so that the resulting shoe is built up of a number of isolated sections, the spacing between the sections preventing the completed shoe from straightening out in service and materially increasing the heat-radiating surface thereof. Furthermore, the separate casting of each section allows them to be formed of different metals, obtained from different furnaces, so that each possesses the desired and requisite properties capable of collectively forming a brake shoe possessing long wearing qualities and good frictional properties. The uppermost or end wall of each section, with the exception of the last, accordingly forms the bottom wall of the shoe cavity in which the metal of the next or superposed section is cast. The metal of the various sections is thus allowed to flow throughout the various interstices of the openwork metal, and in addition, becomes securely anchored to the reinforcing back 13. The positioning of the inlet ports 11 substantially central of the sections to which they correspond, minimizes, and 55 practically eliminates, the burning or fusing of the expanded metal 14, as the molten metal quickly engulfs the same immediately in front of the inlet ports 11, and so protects the same from direct contact with the inflowing metal. As far as the burning of the reinforcing member is concerned, the best position for the inlet ports would be at approximately the lowermost level of each section, but with the ports so arranged, there is

danger of the molten metal becoming cooled as it rises in the shoe cavity. With the inlet ports arranged as illustrated, the molten metal flows throughout the various interstices of the reinforcing member and produces a uniform and homogeneous casting, and without excessive burning or fusing of the reinforcing member. By arranging the molds in batteries, the casting of a large number of shoes can be efficiently carried out, the corresponding sections of all shoes being cast at the same time. The different sections of each shoe are preferably formed of hard and soft metals, although the number of sections, their arrangement, and the characteristics or properties of the metals of which they are formed, may be varied as desired.

What I claim is:—

1. The method of forming brake shoes in molds which are provided with the shoe cavity on end and with overflow ports at successive heights, consisting in introducing molten metal within said cavity until the same flows from the lowermost overflow port, allowing said metal to harden, resulting in the closing of the lowermost overflow port, introducing a second allotment of molten metal within said cavity until it flows from the next adjacent and superimposed overflow port, allowing said metal to set and in this manner build up, step by step the body of the shoe.

2. The method of forming brake shoes of that type which includes a bundle of open-work metal extending throughout their length, consisting in placing the mold in a position with the shoe cavity on end, introducing within said cavity a bundle of open-work metal, and pouring therein, and at subsequent times, limited quantities of molten metal.

3. The method of forming brake shoes consisting in introducing, at successive intervals, limited quantities of molten metal within a mold having a shoe cavity arranged on end, the brake shoe cavity containing a reinforcing back and a binding member, each allotment of metal being allowed to set prior to the introduction of the next allotment.

4. The method of forming castings as hereinabove described, consisting in introducing molten metal within a mold cavity, which cavity is provided with overflow ports at successive heights, allowing said metal to harden, resulting in the closing of the lowermost overflow port, introducing a second allotment of molten metal within said cavity until it flows from the next adjacent and superimposed overflow port, allowing said metal to set and close this latter-mentioned overflow port, and in this manner build up, step by step, the body of the casting.

5. The method of forming brake shoes,

consisting in placing a mold in a position with the shoe cavity on end, placing within said cavity a supporting member, introducing at successive intervals limited quantities 5 of molten metal, allowing each allotment of metal to set prior to the introduction of the next allotment, the anchorage of each allot-

ment of metal to said supporting member causing the isolation of the former by the shrinkage of the metal during cooling.

Signed at New York, in the county of New York and State of New York, this 20 day of May, A. D. 1915.

HARRY JONES.
